UNITED STATES PATENT OFFICE.

GEORGE G. GOING, OF MIDDLETOWN, CONNECTICUT, ASSIGNOR TO REMINGTON-NOISELESS TYPEWRITER CORPORATION, OF NEW YORK, N. Y., A CORPORATION OF NEW YORK.

TYPEWRITING MACHINE.

Application filed August 19, 1925. Serial No. 51,125.

My invention relates primarily to carriage bearings for typewriting machines, and its main object is to provide new and improved carriage or like bearings for such machines.

To the above and other ends which will hereinafter appear, my invention consists in the features of construction, combination of devices, and arrangements of parts 10 hereinafter described and particularly pointed out in the claims.

In mounting the carriage of a typewriting machine on its support or bearing, it is highly important, in order to obtain the 15 best results, that the carriage and its bearings shall be so related that the carriage may move freely back and forth during its travels and yet not be so loose that it is not firmly supported. The difficulty comes in 20 so adjusting the carriage to its bearing that there shall be no rattle or undue looseness on the one hand, and, on the other hand, that it may not be so tightly held that it will bind, check or move sluggishly during 25 its travel. In order to facilitate the proper co-relationship between the carriage and its mounting, which in the present instance comprises two relatively adjustable rails or ways. I provide for connecting the rail 30 parts together at their ends by means of tie-pieces or links, which co-operate with eccentrics to afford fine or nice adjustments of the rail parts. Then after they have 35 been suitably co-related by means of the tie-pieces and eccentrics, the rail parts are secured together at intervals along their 40 lengths by clamping screws, the tie-pieces and eccentrics holding the rail parts against relative displacement while the screws are being tightened to fix said parts in permanent relationship.

The invention will be described in detail in connection with the accompanying drawings, wherein—

Figure 1 is a fragmentary transverse sectional view of the carriage and mounting of a No. 6 Remington-Noiseless typewriting machine, to which my invention is shown as applied.

Figure 2 is a plan view of said carriage and its mounting or bearing, parts being broken away for the sake of clearness.

Figure 3 is a fragmentary end view showing the carriage bearing as seen from the

right-hand end, the carriage bar being 55 shown in section and the parts being drawn to a larger scale than Fig. 1.

Figure 4 is a fragmentary sectional view taken on a plane indicated by the section line 1—1 in Figure 2, and looking in the 60 direction of the arrows at said line, Figure 4 being drawn to a larger scale than Figure 2, however.

Figure 5 is a fragmentary sectional view taken on a plane indicated by the section 65 line 2—2 in Figure 4 and looking in the direction of the arrows at said line.

Figure 6 is a fragmentary perspective view of the carriage bearing and certain of the adjusting devices, the parts being separated or spread for the sake of clearness.

In the machine the usual platen 1 is mounted on a carriage comprising end bars 2 which are connected below the platen by a cross bar 3. The cross bar is oppositely 75 grooved at its front and rear to receive anti-friction rollers 4 which co-operate also with a carriage supporting member. In the present instance the supporting member is trough-like in cross-section and comprises 80 two guide rail parts or elements which are adapted to be adjustably secured together. The front or main part 5 is angularly shaped in cross-section comprising an upright portion and a horizontally disposed or 85 bottom portion, the two portions being integrally formed. The other or secondary part 6 is at the rear and is adapted to be adjustably fixed to the main part 5 in a 90 novel manner hereinafter described. The parts 5 and 6 comprising the carriage rail or trackway are oppositely grooved to provide ways for the anti-friction rollers 4 whereby the carriage is adapted to move or 95 travel endwise along the rails during typewriting operations. At the under side of the rail, lugs 7 project downwardly from the horizontal portion of the part 5 and are pivotally connected at 8 with arms 9 which are secured to a rock shaft 10, said shaft 100 bearing in parts 11. The shaft 10 is adapted to be rocked to shift the carriage rail 5, 6, the carriage 2, 3, and the platen 1 up and down to change case, as fully disclosed in my pending application Sr. No. 14,100, filed 105 March 9, 1925.

Arranged between the rail parts 5 and 6 is a rack plate 12 which is one of the ele-

ments of roller controlling mechanism whereby the anti-friction rollers 4 are maintained properly spaced apart during the carriage travel. The rack 12 is clamped 5 between the rail parts by the rail-securing devices.

The rail securing devices comprise headed screws 13 which are arranged at intervals along the carriage rail or bearing, in the 10 present instance four of these screws being shown. The screws pass upward freely through enlarged holes 14 in the rail part 5 and are threaded into tapped openings in the rail part 6. Washers 15 are arranged 15 between the heads of the screws 13 and the under face of the rail part 5, these washers covering the bottoms of the holes 14. Said holes are of such diameter as to afford the necessary variation in the relationship of 20 the two rail parts 5 and 6 in a horizontal direction. It will be understood that when the screws 13 are tightened, the rail parts 5 and 6 are securely held in fixed relationship, and also when the screws are loosened the 25 space between the shanks of the screws and the walls of the holes 14 will permit the rail part 6 to be moved a slight distance back and forth in a horizontal direction on the part 5. The heads of the screws 13 may be hexagonal as shown to facilitate adjustments.

In order to hold or secure the rail parts when the screws 13 are loose or are not in place, means are provided comprising tie pieces or links 16 arranged at the ends of 30 the rail parts. The tie pieces are horizontally disposed and lie against the ends of the two-part rail. At their forward ends the tie pieces are secured to the ends of the rail parts 5 by headed screws 17, these screws 35 when loose affording a pivotal movement of the tie pieces, since the holes 18 in the tie pieces, through which the shanks of the screws pass, are not tapped, only the holes 19 in the rail part 5 being threaded to co-operate with the threads of the screws. At 40 their rear end portions the ties or links 16 are enlarged, as indicated at 16^a, and are adapted to be secured to the rail parts 6 by screws 20. These screws co-operate indirectly, however, with the tie pieces. They 45 co-act directly with eccentric devices composed each of a hexagonal head 21 and a cylindrical body portion 22, which fits rotatively in a hole or eye in the part 16^a of the 50 associate tie piece. The shanks of the screws 20 pass freely through smooth openings 24 in the associate eccentric devices 21, 22, each hole 24 being eccentrically related to the cylindrical portion 22. After passing through 55 the hole 24 the shank of the screw 20 is threaded into a tapped opening 25 in the end of the rail part 6. The construction is such that when the screws 20 are tightened, the 60 heads 20 thereof exert a pressure against the heads or flanges 21 of the eccentrics, which

pressure is transmitted by the opposite or inner faces of the heads 21 to the outer faces of the tie plate portions 16^a, thus clamping the tie-pieces between the eccentric heads 21 and the faces of the rail parts 6. In order 70 to insure an effective clamping action the depth of the eccentric part 22 is less than the depth of the hole 23, as is clearly apparent from Fig. 4, so that the inner face of the eccentric cannot contact with the face of the 75 part 6, thus preventing any possible looseness between the eccentric heads 21 and the rail parts 6 when the screws 20 are tightened.

From what has been said, it will be understood that preliminary to adjustment the screws 13 are held loosely in place and the screws 17 and 20 are also loose so that the tie pieces or eccentric straps 16, 16^a, are free or unclamped. With the parts so related it is apparent that by applying a tool to the eccentric heads 21, the eccentrics may be turned slightly in either direction, thus reacting on the tie pieces or straps 16 through the holes or eyes 23, causing the tie-pieces 90 either to draw the rail parts slightly closer or to force them slightly further apart. This enables nice adjustments of the rail parts 5, 6 to be made with ease and facility so that they will co-operate through the anti-friction rollers 4 with the carriage bar 3 to obtain exactly the results desired, enabling the carriage to move freely in its bearings and yet holding it so that undue looseness is prevented. When the rail parts have been 100 adjusted in the desired relationship the screws 20 and 17 at the opposite ends of the rail parts are tightened, thus securing the rail parts at their ends in adjusted relationship. The screws 13 may thereafter be 105 tightened to permanently set or fix the rail parts throughout their lengths without disturbing their adjustments, the eccentrics and the tie-pieces serving as holding devices to hold the two parts of the bearing pending this tightening of the clamping screws or securing devices 13.

Various changes may be made without departing from my invention.

What I claim as new and desire to secure by Letters Patent is:—

1. In a typewriting machine, the combination of a two-part carriage bearing, separate connecting tie-pieces arranged at opposite ends of said two-part bearing, and means for securing the tie-pieces to the two parts of the bearing, said means comprising eccentric devices.

2. In a typewriting machine, the combination of a traveling carriage, carriage rails, and means for adjustably securing said rails in fixed relationship, said means comprising a pair of tie-pieces and co-operating eccentric devices, said tie-pieces being arranged at opposite ends of the carriage rails.

3. In a typewriting machine, the combination of a traveling carriage, a two-part carriage rail, and means for adjustably securing said rail parts in fixed relationship, said means comprising tie-pieces separate from both parts of said carriage rail and adjustably connecting the ends of said two parts.
4. In a typewriting machine, the combination of a traveling carriage, a two-part carriage rail, devices arranged at intervals lengthwise of the two rail parts for adjustably securing them together, and adjustable devices for variably holding the two parts in desired relationship before said securing devices are rendered effective.
5. In a typewriting machine, the combination of a traveling carriage, carriage rails, devices arranged at intervals lengthwise of the two rails for securing them together, and adjustable devices for holding the rails in desired relationship before said securing devices are rendered effective, said adjustable devices comprising tie-pieces arranged at the ends of the rails.
6. In a typewriting machine, the combination of a traveling carriage, guide rails therefor, devices arranged at intervals lengthwise of said rails for securing them together, and holding devices for holding said rails in desired relationship before said securing devices are rendered effective, said holding devices comprising tie-pieces arranged at the ends of the rails and eccentric devices adjustable on one rail and co-operating with end portions of the tie-pieces.
7. In a typewriting machine, the combination of a traveling carriage, a two-part carriage rail comprising an angular main part and a secondary rail part, clamping screws for securing the two parts together in adjusted relationship, said screws being arranged at intervals lengthwise of the two parts and passing through enlarged holes in one part to engage in threaded openings in the other part, and holding devices for holding the two parts in desired relationship before the screws are tightened, said holding devices comprising links pivotally connected at their ends to the two parts.
8. In a typewriting machine, the combination of a traveling carriage, a two-part carriage rail comprising an angular main part and a secondary part, clamping screws for securing the two parts together in adjusted relationship, said screws being arranged at intervals lengthwise of the two parts, and holding devices for holding the two parts in desired relationship before the screws are tightened, said holding devices comprising links pivotally connected at their ends to the two parts and also eccentric devices adapted to be clamped to one of the parts and co-operating with end portions of said links.
9. In a typewriting machine, the combination of a traveling carriage comprising a grooved bar, a platen on said carriage, a trough-like carriage rail composed of a main part and a secondary part, said parts being provided with oppositely facing grooves, anti-friction rollers co-operating with said grooves and also with said grooved carriage bar, screws arranged at intervals lengthwise of the two rail parts and adapted to clamp them together in fixed variable relationship, tie links arranged at the ends of the two rail parts, screws one for securing the end of each tie link to said main part, eccentric devices co-operating with eyes in the other ends of said tie links, and screws for clamping said eccentric devices adjustably to the secondary rail part.
10. In a typewriting machine, the combination of a traveling carriage, separate guide rail parts along which the carriage travels, and means adjustably connecting said rail parts at their ends comprising eccentrics, eccentric straps and devices for clamping said eccentrics and straps after adjustment.
11. In a typewriting machine, the combination of a traveling carriage, separate guide rail parts along which said carriage travels, securing devices for securing the rail parts together at their ends, and other securing devices for securing the rail parts together at intervals along their lengths, the end-securing devices being adjustable and serving also as holding devices pending the tightening of said other securing devices.

Signed at Middletown, in the county of Middlesex, and State of Connecticut, this 15th day of August, A. D. 1925.

GEORGE G. GOING.
